UNITED STATES PATENT OFFICE.

ADELBERT E. ELLIS, OF LAWRENCE, ASSIGNOR TO JAMES W. BROOKS,
TRUSTEE, OF CAMBRIDGE, MASSACHUSETTS.

HEELING-MACHINE.

SPECIFICATION forming part of Letters Patent No. 388,544, dated August 28, 1888.

Application filed March 10, 1888. Serial No. 266,859. (No model.)

To all whom it may concern:

Be it known that I, ADELBERT E. ELLIS, of Lawrence, in the county of Essex and State of Massachusetts, have invented an Improvement 5 in Heeling Machines, of which the following description, in connection with the accompanying drawings, is a specification, like letters on the drawings representing like parts.

In machines for nailing and trimming heels, 10 of which class of machines the so-called "Mc-Kay and Bigelow" is a type, the nail-box, upon the top of which is pivoted the usual top-lift plate, has a rod fixed to it, which enters the hollow shank of a driver-plate, the latter 15 resting immediately above the usual trimmer-lever, the shank of the driver-plate being connected with a rising and falling spindle. The driver-plate referred to also has located upon it a fixed pin, which enters a hole in the nail-box, the said hole being more or less distant 20 from the rod attached to the nail-box. The shape or contour of the nail-box and its top or pattern plate varies materially, they having to be shaped to correspond with the particular 25 shape of the heel to be trimmed, and hence very many nail-boxes have to be employed with each machine. In practice each particular shape and size of nail-box has to have a particular driver-plate to work with it, because of the fixed pin erected upon the driver-plate. The object of my invention is to obviate 30 the employment of a great number of driver-plates, and this I have done by making the pin referred to adjustable with relation to the driver-plate, so that one driver-plate with 35 a movable pin may be employed with many sizes and shapes of nail-box.

My invention consists, essentially, in the combination, with the nail-box having a rod 40 and hole and a driver-plate, of a guide-pin adjustably connected to the driver-plate to enter the hole in the nail-box, as will be described.

Figure 1 in side elevation represents a nail-box and its shank and top-lift plate, the said 45 driver-plate having a movable guide-pin embodying my invention, the shank of the driver-plate being broken out in the drawings. Fig. 2 is a top view of the driver-plate with the adjustable guide-pin; Fig. 3, a section of Fig. 2

in the line xx ; and Fig. 4 shows an under side 50 view of the nail-box.

The driver-plate d , its sleeve-like shank e , the top-lift plate a , pivoted in usual manner upon the nail-box c , and the rod l , fixed to the nail-box and extended down into the shank e 55 of the driver-plate, and the top plate, b , of the nail-box, are all substantially as in common use upon the machine referred to.

Viewing Fig. 4, it will be noticed that the nail-box has a hole, n , at some distance from the rod l . In practice the rod l is attached to the nail-box nearly at the center of the box, no matter what may be the size of the box, that depending upon the size of the heel. The nail-box has to be held in such manner upon the driver-plate as not to be twisted aside when the nail-box is lifted above the driver-plate by the usual spring, which acts upon the end of the rod l . In practice the hole n in the nail-box varies as to its distance from the rod 70 l , according to the size and shape of the nail-box, that depending upon the size and shape of the heel to be trimmed.

When the rod l is fixed and the hole n in the box varies as to its distance from the rod l , 75 then the box must have co-operating with it a driver-plate in which the shank e shall be properly located to receive the rod l , and the guide-pin, which has been fixed to the driver-plate, must also occupy just the right position 80 thereon to enter the hole n , and as the result of all this it has been customary to have with each nail-box a separate driver-plate.

To enable one driver-plate to be employed with the nail-boxes of various sizes and shapes, 85 I have so made the guide-pin f that it may be adjusted upon the driver-plate to and from the center of the sleeve-like shank e of the driver, and by so doing the guide-pin may be made to enter the hole n in the nail-box, no matter 90 what may be the size and shape of the nail-box.

As herein represented, the guide-pin f has a dovetailed foot, g , somewhat elongated, which slides in a correspondingly-shaped groove in the nail-box, and, as herein shown, each end 95 of the foot is made concave to fit against the rod l when inserted in the shank e , and the foot may be inserted either end first into its

guideway, according to the particular position required for the guide-pin.

I claim—

1. The combination, with a nail-box having a rod and hole and a driver-plate, of a guide-pin adjustably connected to the driver-plate to enter the hole in the nail-box, substantially as described.

2. In a nail-box, the combination, with a driver-plate having a tubular shank, of an ad-

justable guide-pin connected to the said plate, substantially as described.

In testimony whereof I have signed my name to this specification in the presence of two subscribing witnesses.

ADELBERT E. ELLIS.
